COMBINED CABINET, WORK TABLE AND ROOM PARTITION UNIT

Ole H. Christensen and William P. Merci, Chicago, Ill.,
assignors to Exchange National Bank of Chicago, a
national banking association

Filed June 8, 1966, Ser. No. 2,603

Term of patent 14 years

(Cl. D33—19)

FIG. 1

FIG. 3

FIG. 2

FIG. 4

FIG. 6

FIG. 5

FIGURE 1 is a perspective view of a combined cabinet, work table and room partition unit showing our new design;

FIGURE 2 is a front elevational view of FIGURE 1;

FIGURE 3 is a side elevational view of FIGURE 1 as viewed from the left;

FIGURE 4 is a side elevational view of FIGURE 1 as viewed from the right;

FIGURE 5 is a top plan view of FIGURE 1;

FIGURE 6 is a rear elevational view of FIGURE 1.

The dominant features of our invention reside in those portions shown in full lines on the drawings.

We claim:

The ornamental design for a combined cabinet, work table and room partition unit, substantially as shown and described.
